NOVELTY MATCH PACKAGE

Henry L. Freeman, Chicago, Ill.

Application November 15, 1932, Serial No. 642,770

2 Claims. (Cl. 206—29)

The invention relates generally to a match package and more particularly to a book match package.

It is an object of the invention to provide such a device of simple construction and attractive appearance.

Another object is to provide such a combination device in which a member is pivotally mounted on the front flap of a book match package and is arranged to have its lower end inserted with the flap behind the locking tab at the lower end of the package.

Other objects will become readily apparent from the following detailed description taken in connection with the accompanying drawing, in which:

Fig. 1 is a perspective view of a preferred form of the invention, the package being shown open and positioned for use as a place card.

Fig. 2 is a view of the front of the package.

Fig. 3 is a view similar to Fig. 2 but with the pivoted member removed.

Fig. 4 is a side view of the closed package.

For purposes of disclosure I have illustrated in the drawing and shall hereinafter describe in detail a preferred embodiment of the invention with the understanding that I do not intend to limit the invention to the particular construction and arrangement shown, it being contemplated that various changes may be made by those skilled in the art without departing from the spirit and scope of the appended claims.

In the form illustrated in the drawing, a match package is shown having a cover comprising a back portion 10, a lower retaining tab 11, an upper portion 12, and a front flap 13 the lower edge of which is inserted behind the retaining tab. The usual strips or combs of matches 14 are secured within the package by means of a suitable clip 15 at the lower or retaining tab end. The portions 10, 11, 12 and 13 of the package are formed or bent from a single strip of material and preferably the tab 11 is folded over at its upper end 16 and extends downwardly under the lower end of the flap 13 and upwardly in the form of a shield or guide 17. Ordinarily when the matches are torn off the stub ends make it difficult to insert the flap 13 behind the tab 11. However, by extending the guide or shield portion 17 above the upper end of the tab 11 the insertion of the front flap is greatly facilitated.

As illustrated in the drawing, a card-like member 20 is pivotally mounted on the front flap 13 by means of a fastening device 21. Normally when the match package is closed the lower end

22 of this pivoted member is inserted behind the tab 11 with the flap 13 as illustrated in Fig. 4. When the package is used as a place card, the pivoted member is aligned with the front flap 13 as illustrated in Fig. 1. A panel 23 on the upper portion 12 of the package is then arranged so that a name can be inserted.

In its preferred form the invention is adapted for use in calculating scores for contract bridge. Thus the front flap 13 of the package is herein provided with somewhat radially extending columns of numerals 25, 26, 27, 28 and 29 which are visible selectively through a somewhat radial slot 30 in the pivoted member 20. The uppermost numeral in each column indicates the number of under tricks and the succeeding numerals downwardly in the column, in combination with ciphers on the member 20 adjacent the slot 30, indicate the penalties "not vulnerable, not doubled", "not vulnerable, doubled", "vulnerable, not doubled" and "vulnerable, doubled", respectively. To the right of the penalties are positioned trick values for the various suits. Other information regarding scoring may be placed on the lower portion 31 of the front flap 13 and the lower portion 22 of the pivoted member 20, and if desired additional information may be placed on the back 10 of the inside of the front flap.

Preferably the pivotal fastener 21 is positioned eccentrically of the columns 25 to 29, inclusive, as illustrated in Fig. 3 so that when the member 20 is pivoted the ciphers thereon align accurately with the numerals in the columns. Herein the pivot fastener is positioned vertically above the first row of ciphers adjacent the slot 30.

I claim as my invention:

1. A book match package having, in combination, a comb of matches, a cover comprising a strip of material with its intermediate portion passing in back of the matches, a short end bent up in front of the supporting ends of the matches and secured thereto to form a retaining tab, and its other end extending over the match heads and down in front thereof to form a front flap arranged to have its lower end inserted behind said retaining tab, said flap being provided with informative data thereon and a member pivotally secured at its upper end to said front flap so as to overlie the flap and have its lower end inserted behind said tab, and having an aperture therein through which said data on said flap are visible when said member is pivoted with respect to the flap, said retaining tab holding said flap and member together against relative swinging movement.

when the flap and member are inserted behind the tab.

2. A book match package having, in combination, a comb of matches, a cover comprising a strip of material with its intermediate portion passing in back of the matches, a short end bent up in front of the supporting ends of the matches and secured thereto to form a retaining tab, and its other end extending over the match heads and

down in front thereof to form a front flap arranged to have its lower end inserted behind said tab, a member pivotally secured to said front flap so as to overlie the flap and have its lower end inserted behind said tab, said flap having informative data thereon visible when said member is swung relatively to the flap.

HENRY L. FREEMAN.
